CLAIM

I claim the ornamental design for a pest free pet feeder, as shown and described.

DESCRIPTION

FIG. 1 is a perspective view of the pest free pet feeder showing my new design;

FIG. 2 is a side elevational view, the opposite side being a mirror image thereof;

FIG. 3 is a top view thereof, showing the multiple layers of the feeder;

FIG. 4 is a side sectional view of the feeder;

FIG. 5 is an exploded view of the feeder illustrating the order of assembly; and,

FIG. 6 is a bottom view of the feeder.
